UNITED STATES PATENT OFFICE.

WESLEY SLAYDEN, OF WICHITA, KANSAS.

CAR-COUPING.

No. 823,643.

Specification of Letters Patent.

Patented June 19, 1906.

Application filed January 2, 1906. Serial No. 294,208.

To all whom it may concern:

Be it known that I, WESLEY SLAYDEN, a citizen of the United States, residing at Wichita, in the county of Sedgwick and State of Kansas, have invented certain new and useful Improvements in Car-Couplers, of which the following is a specification.

The object of my invention is to provide an improved construction of car-coupler which will render the coupling and uncoupling of the cars safe and avoid the probability of injury to the operators, which embodies improved means whereby the cars may automatically couple themselves when coming together, and which embodies a new and useful arrangement and combination of the parts and certain details of construction herein-after fully described, and specifically set forth in the accompanying claims.

For a full description of the invention and the merits thereof and also to acquire a knowledge of the details of construction of the means for effecting the results reference is to be had to the following description and accompanying drawings, in which—

Figure 1 is a side elevation of the meeting ends of two cars equipped with my improved car-coupler. Fig. 2 is a detail view, on an enlarged scale, of the two meeting draw-heads in section and with the coupling parts in side elevation. Fig. 3 is a detail perspective view of my improved coupling-link. Fig. 4 is a detail perspective view of one of the draw-heads.

Corresponding and like parts are referred to in the following description and indicated in all the views of the drawings by the same reference characters.

Referring to the drawings, the numeral 1 designates the meeting portions of two cars that are equipped with my improved construction of coupler. The draw-head 2 of one of said cars is a box-like or hollow structure provided with an open outer end and with two recessed sides forming outwardly-facing ledges 3 near the edge thereof, with a beveled lower front edge 4 and with a preferably rectangular opening 5 extending through its bottom adjacent the said front edge. The said draw-head 2 is also provided with a hinged top or lid 6, the said lid being hinged to the draw-head proper at or near the rear end of the former and being provided at its opposite end facing the end of the draw-bar 5 with a beveled edge on its under side, (desig-

nated 7,) with a loop or eye 8 in said edge and with a preferably rectangular opening 9 extending entirely therethrough and in vertical alinement with the opening 5 when the lid 6 is in closed position with respect to the draw-bar. In said position the lid 6, which, as shown, is in the form of a flat plate, rests upon the ledges 3. The sides of the draw-bar that constitute the ledges 3 are preferably recessed near the inner end of the box-like draw-bar 2 or terminate short of said end, as illustrated, forming a curved rear edge 10. The opposite draw-bar 2^a is hollow for a portion of its length to provide a longitudinally-extending socket for the reception of one end of the coupling-link 11, said link being provided at one end with an aperture or socket 12, through which the pin 13 is inserted, said pin being also inserted through the draw-bar 2^a, so as to detachably connect the said end of the link in the draw-bar. The pin 13 is of sufficient smaller diameter than the opening 12 of the link through which it extends as to permit the link to be rocked in a vertical plane, and the rear lower edge of the link is beveled, as shown at 14, to limit the upward movement of the opposite end of the link in connection with the walls of the openings 12.

The link 11, as shown, projects forwardly out of the draw-bar 2^a and at its free end is provided with a spear-head portion, consisting of upper and lower vertical wings 15, having oppositely-beveled edges 15^a and two horizontally-extending wings 16, also provided with oppositely-beveled front edges 16^a.

As shown in Fig. 1, plates 17 are secured to the meeting ends of the cars and are provided with brackets 18, recessed, as at 19, to constitute bearings for a transverse shaft. A ratchet 21, operated by a crank 22, is designed to actuate the shaft over which the chains 25 are wound. One of the chains is secured to the loop or eye 8 at the free end of the plate 6, and the other is connected to a loop or eye 26 of the coupling-link 11. Pawls 23 are designed to coact with the ratchets 21, and plates 24 are secured to said pawls.

In the practical operation of my improved car-coupler as the cars come together the spear-head link 11, by means of its vertically and horizontally extending wings with their front beveled edges, will accurately find the opening in the end of the draw-bar 2 and enter the said draw-bar with the lowermost wing 15 riding over the beveled edge 4 and

with the beveled front edge of the upper wing 15 riding upon the beveled edge 7 of the plate 6, and thereby tilting the outer end of the plate upwardly. As the link continues 5 to move into the draw-bar 2 the wings 15 will finally pass into the openings 5 and 9, which will permit the plate 6 to drop to its normal locking position and will hold the two cars securely together by means of the spear-head 10 end of the link 11 engaging the walls of the said openings, as indicated in Fig. 1. To uncouple the cars, it is only necessary to turn one of the cranks 22. This will raise the free end of the plate, so as to disengage the latter 15 from the upwardly-extending wing 15 of the link 11, and then by the similar swinging up of the other cord 25 the link 11 may be raised until its lower wing 15 is disengaged from the wall of the openings 5 in the bottom of the 20 draw-bar 2. Then the cars, as is manifest, will readily separate.

From the foregoing description, in connection with the accompanying drawings, it will be seen that I have provided an improved 25 construction of car-coupler which is automatic in its coupling operation and which will insure the coupling of the cars automatically upon curves or under conditions where one draw-head is above the other by reason 30 of the centering function of the spear-head end of the link 11.

Having thus described the invention, what is claimed as new is—

1. A car-coupler having in combination 35 two draw-heads one of which is hollow and is provided with a hinged portion and with an opening therein and in said portion, a link secured to the other head and provided with an end arranged to be locked in said two 40 openings, a manually-operable cord or chain secured to the free end of said hinged portion to raise the same, and another manually-operable cord or chain attached to the link and arranged to lift the latter, the said two cords

being operatively connected to the two re- 45 spective cars carrying said draw-heads.

2. A car-coupler having in combination two draw-heads, one of which is hollow and is provided with a hinged portion and with registering openings in its bottom and in said 50 hinged portion, a link secured to the other draw-head and arranged to be locked in said openings, means for raising the hinged portion of the hollow draw-head, and independent means for lifting the link.

3. A car-coupler comprising a hollow draw-head provided with a hinged portion and with an opening in its bottom and also in said hinged portion, a link arranged to be detachably secured in another draw-head and provided at its attached end with a beveled lower edge 14, the said link being arranged to rock vertically on the said beveled lower edge and being provided at one end with oppositely-beveled wings designed to enter the 60 first-named draw-head, whereby the hinged portion thereof may be automatically raised and the said wings find lodgment in the openings in said hinged portion and in the bottom of the draw-head.

4. A car-coupler having in combination two draw-heads one of which is hollow and is provided with a hinged portion and with registering openings in its bottom and in said hinged portion, a link secured to the other draw-head and provided with an end arranged to be locked in said openings, a manually-operable cord or chain secured to the free end of said hinged portion to raise the same, and another manually-operable cord or chain 70 attached to the link and arranged to lift the latter, as and for the purpose set forth.

In testimony whereof I affix my signature in presence of two witnesses.

WESLEY SLAYDEN. [L. S.]
